UNITED STATES PATENT OFFICE.

LOUIS BELTRAMINI, OF CHICAGO, ILLINOIS.

NONSEPARATING RAIL CONNECTION.

1,413,378.

Specification of Letters Patent. Patented Apr. 18, 1922.

Application filed November 20, 1920. Serial No. 425,461.

To all whom it may concern:

Be it known that I, LOUIS BELTRAMINI, a citizen of the United States, residing at Chicago, in the county of Cook and State of Illinois, have invented certain new and useful Improvements in a Nonseparating Rail Connection; and I do hereby declare the following to be a full, clear, and exact description of the invention, such as will enable others skilled in the art to which it appertains to make and use the same.

The object of the invention is to provide a rail joint or connection which can be operated and used without the assistance of fish plates, rail chairs or like contrivances and which will adapt the rail sections or members to be readily connected in series under such conditions that the only fastening means required are the spikes by which they are secured to the ties as in the ordinary practice; to provide a rail joint or connection which can readily be constructed as a part of the rail section; to provide a joint or connection which will effectually prevent separating or relative displacement of the adjoining rail ends; and to provide a means of connection between adjoining rail sections or members which can be operated to effect the interlock of the rail ends by tilting or inclining the loose rail, engaging the extremities of the sections or members by an endwise movement and then dropping or lowering the elevated free end of the rail to its position upon the ties, so that the rail sections or members can be connected in series or consecutively to provide for the progressive laying of the track and avoid returning to previously positioned rail sections in order to complete the operation of securing the same; and with these objects in view the invention consists in a construction and combination of parts of which a preferred embodiment is shown in the accompanying drawing, wherein

Figure 1 is a side view of a section of track rail wherein the members are constructed in accordance with the invention and showing the adjoining ends interlocked as in practice.

Figure 2 is a detail longitudinal sectional view of a joint showing the members in their normal or interlocked position.

Figure 3 is a side view showing the loose rail, or the rail member which is about to be applied or laid, arranged in the tilted position which it assumes in order to effect the interlock.

Figures 4 and 5 are detail views respectively of the mating or supplemental rail ends.

The extremities of each rail member shown at 10 are provided with mating or supplemental interlocking members indicated respectively at 11 and 12 and shown respectively in detail in Figures 4 and 5, so that the adjacent extremities of two adjoining rail members may be interlocked to provide against relative lateral and longitudinal displacement, the male element having a tongue 13 for reception by a seat 14 of the other element, the terminal of the tongue being upwardly deflected to provide a nose 15 for engagement with a recess 16 at the inner end of the seat 14, the inner side of the nose constituting an abrupt shoulder 17 for engagement with a correspondingly abrupt wall 18 of said recess. The under side of the tongue is convexly curved as indicated at 19 to fit the concavely curved lower wall 20 of the seat, so that when the rail member which is about to be positioned is disposed in an inclined or tilted position indicated in Fig. 3, the nose or free end of the tongue 13 may be introduced into the seat 14 and moved longitudinally thereof until as the rail is gradually lowered toward a horizontal position upon the ties (not shown), the tongue slides inwardly upon the concaved wall 20 of the seat and the nose 15 finds its position in engagement with the recess 16 with the shoulders 17 and 18 in opposing relation to lock the rail ends against longitudinal displacement.

At the sides of the seat 14 and constituting the side walls thereof are ears 22, preferably formed by thickened or reinforced portions of the rail web 23 and extending beyond the end of the rail to overlap the side surfaces of the web of the adjoining rail member as indicated in Figure 1, the extremities of said ears being rounded as indicated to facilitate their entrance between the rail head 24 and rail foot 25 as the rail member which is being applied (as shown in Figure 3) is swung from the inclined position to the position in alignment with the rail member which has already been positioned, preparatory to securing the rail member to the ties by means of spikes as in the ordinary practice.

From the foregoing description it will be obvious that in laying a track the rail members may be successively positioned and each member as it is applied may be interlocked

terminally with the previously positioned member by disposing the end of the former in interlocking relation with the adjacent end of the previously laid member while the 5 later applied member occupies the inclined or tilted position indicated in Figure 3, and when the tilted member has been swung downward into position upon the ties, it may be securely fastened in the ordinary way by 10 means of spikes, and the succeeding rail member applied to the free end thereof, so that the rail members successively positioned may be fastened as the work progresses and may be removed or taken up successively in 15 the reverse order, and when interlocked the joints are transversely reinforced to guard against separation or distortion.

Having thus described the invention, what I claim is:—

20 A joint for rails, one end of one of the rails having a projection with an arcuate lower edge wall extending from the junction

at such end, the adjacent end of the complementary rail having a recess of similar shape to that of the projection to receive the said projection upon downward turning of the first mentioned rail after abutment of the proximate ends of said first and complementary rail, interfitting means between the projection and complementary rail consisting 25 of an upward extension on said projection having a curved wall in continuance of said arcuate lower edge, and projecting means on said complementary rail extending intermediate and engaging the base and tread 30 flanges of the first rail as the rails are joined to prevent relative movement thereof at the joint.

In testimony whereof I affix my signature, in presence of two witnesses.

LOUIS BELTRAMINI.
